UNITED STATES PATENT OFFICE.

ANDREW H. STONE, OF KANSAS CITY, MISSOURI.

COMBINED LIBRARY AND DINING TABLE.

1,334,415.

Specification of Letters Patent. Patented Mar. 23, 1920.

Application filed November 9, 1917. Serial No. 201,853.

To all whom it may concern:

Be it known that I, ANDREW H. STONE, of Kansas City, Jackson county, Missouri, and a citizen of the United States, have invented 5 certain new and useful Improvements in Combined Library and Dining Tables, of which the following is a specification.

This invention relates to combined library and dining tables and my object is to produce a combination table which in either of its forms shall constitute a strong and rigid structure, and which can be easily and quickly converted from one form into the other form. A further object is to produce 15 a convertible table of this type which is of attractive appearance in either form and which is of simple and inexpensive construction.

With these objects in view, the invention 20 consists in certain novel and useful features of construction and combinations of parts as hereinafter described and claimed; and in order that it may be fully understood, reference is to be had to the accompanying 25 drawings, in which:—

Figure 1, is a top plan view of a structure when arranged as a dining room table, the figure showing one of the wings of the extension of the table, folded back to disclose 30 the relation of certain underlying parts otherwise hidden in said figure.

Fig. 2, is a fragmentary plan view showing certain adjustments of parts necessary to be made in converting the structure from 35 a library table into a dining table.

Fig. 3, is a side view of the structure as arranged in Fig. 2.

Fig. 4, is an enlarged vertical section taken on the line IV—IV of Fig. 5.

Fig. 5 is a vertical section on the same scale as Fig. 4, but taken on the line V—V of Fig. 4.

Fig. 6, is a top plan view on a still larger scale, of one corner of the table, with the 45 top omitted.

Fig. 7, is a vertical section taken on the line VII—VII of Fig. 4.

Fig. 8, is a vertical section on the same scale as Fig. 6, on the dotted line VIII, 50 to show the construction of the table top latches.

Fig. 9, is an inverted plan view of the table with the legs thereof in section at one end and omitted at the other end.

Fig. 10 is a fragmentary perspective view 55 of one of the upper corners of the leg frame.

Fig. 11, is a broken plan view on an enlarged scale of one of the latches for securing the table top extension wings in operative position.

Referring now to the drawings in detail, 1 indicates the framework of the table, and 2 beading strips at the lower edge thereof, said framework being of rectangular form and braced near its ends and parallel therewith by crossbars 3 and a longitudinal bar 4, the former extending from the lower edge of the rear wall of the frame to the bar 4 to which bars 3 are tongued and grooved or otherwise rigidly connected, said longitudinal bar 4 being secured to the front wall of 60 said frame at the lower margin thereof. Mounted upon the crossbars 3 and rigid therewith, are vertical ribs 5 which extend 65 from the front to the back wall of said framework.

At points intermediate the ribs 5 and the adjacent end bars of the framework, the front and back walls of the latter are formed 70 at their inner sides with vertical grooves 6 and outward of the plane of each pair of 75 said grooves, blocks 7 are secured to the end bars of the framework at the inner sides of said bars and secured to the framework at the inner side of the back wall thereof are 80 blocks 8, the said blocks and grooves in conjunction with the framework providing 85 for the attachment of the latter to the leg or supporting framework hereinafter described. Secured to each rib 5 at the outer 90 side thereof is a bar 9, the rear ends thereof sloping downward and rearward to form cams 10. The upper edges of said bars preferably slope at a slight angle upwardly and 95 forwardly to form inclined ways 11, and the front ends of the said bars are spaced rearwardly from the front wall of the table to form pockets 12. (See Fig. 4.)

Secured to each of the ribs 3 vertically 100 above the bars 9, are guide strips 13, the space between each strip 13 and bar 9 constituting a passage 14. (See Figs. 4 and 5.) Secured to the ribs 5 at their inner sides are strips 15, and formed in the upper edges of 105 the said ribs and the said strips 13 and 15 are notches or recesses 16, the same being aligned with each other and with corresponding notches or recesses 17 in the end walls or bars of the framework. The notches 16 and 17 are for the purpose of receiving a 110 depending bead of the table top hereinafter described, when said top is adjusted to the

position it occupies when the structure is arranged as a dining table.

The front wall of the framework from one rib 5 to the other, is recessed as at 18 and normally filling said recess is the front wall 19 of a sliding drawer 20 for holding the extension of the table top as hereinafter more particularly explained. The sides of the drawer are shallower than the wall 19 thereof and rest upon the crossbars 3 and longitudinal bar 4 of the framework and underlie the strips 15, as clearly disclosed in Fig. 5. The back wall 21 of the said drawer corresponds in height to the side walls thereof so that it may slide forward under the retaining strips 15 when the drawer is drawn open. The drawer is provided with a central opening 22 sub-divided by a central strip 23 forming a guide for a sliding element hereinafter described.

Referring now to the supporting or leg frame, 24 indicates four corner legs to fit at the upper ends against the under side of the framework at the four corners thereof, and 25 said legs are provided with upwardly projecting rectangular tenons 25, fitting in the respective corners of said framework, and the tenons at corresponding ends of the framework are connected by cross bars 26 which project beyond the tenons so that they may snugly fit the grooves 6 in the front and back walls of the framework, it being noted in this connection that the blocks 7 act as braces and guides for the 30 crossbars 26 at the outer sides thereof and that the blocks 8 form corresponding guides and braces for said crossbars 26 at the rear ends of the inner sides thereof, and said crossbars 26 are provided in the upper edges 35 with recesses 27 to accommodate a certain pair of blocks hereinafter described and the depending bead of the table top; also hereinafter described, when the said table top is in the position it must occupy when used 40 for a dining table.

The table top 29 is of slightly greater area than the said framework and is provided with a depending bead 30, the front portion of which bead is provided at two points 45 with recesses 31 for the accommodation of a certain part hereinafter mentioned, and for the reception of a finger or two of the person who desires to convert the structure from one form of table to the other, one of said 50 notches being shown in Fig. 4. Secured to the table top at the under side thereof, is a pair of stop-blocks 32, which blocks limit the rearward sliding movement of the table top in the adjustment thereof preliminary 55 to converting the structure from a library table into a dining table, the said stops in said adjustment abutting against the blocks 8 hereinbefore described. In Figs. 1, 2 and 60 3, the table top occupies the adjusted position mentioned and in Fig. 4 such position

is indicated by dotted lines, with blocks 32 against blocks 8.

Angle blocks 33 for operation between ribs 5 and the crossbars 26 of the supporting leg structure, are secured rigidly by 65 screws 34 to and depend from the table top, the front ends of said blocks being tapered downward and rearward so that the blocks shall not bind and interfere with free tilting movement of the table top preliminary 70 to its rearward adjustment mentioned. The blocks 33 are provided with grooves 35 in their upper sides and with vertical grooves 36 communicating with grooves 35, and journaled in grooves 35 and prevented from 75 dislocation from said grooves by the table top itself, are rockshafts 37, the same being provided with crank arms 38 extending downward through the vertical grooves 36 and terminating in forwardly projecting 80 latches or ends 39 for engagement with certain catches hereinafter mentioned. The rockshafts extend forwardly through recesses 40 formed in the upper edge of the front wall of the framework and terminate 85 forward of the framework in crank handles 41 which project into the recesses 31 of the beading of the table top so that one can readily apply upward pressure on said handles and rock said latches sufficiently to 90 disengage them from either of the two catches hereinbefore mentioned but not as yet identified. The latches are held yieldingly advanced by springs 42 bearing against 95 crank arms 38 within the grooves 36, the upper ends of said springs being secured in cross-grooves 43 in blocks 33 by filling strips 44 secured in said cross-grooves.

Projecting inwardly from the blocks 33 near the front lower corners thereof, are pins 100 or rollers 44^a for engagement with the pockets 12 provided at the front ends of the blocks 9, as hereinbefore described. (See Fig. 4.) When the table top is tilted preliminary to adjusting it from its library 105 table position, as shown by dotted lines, Fig. 4, the pins or rollers 44^a are raised out of said pockets so that if rearward pressure is then applied upon the table top, it is free to slide rearwardly because said pins or rollers 110 pass rearwardly through the passages 14, and by gravity, the table top swings downward slowly until the pins or rollers clear the rear ends of the blocks when the front 115 end will swing sharply downward as the pins or rollers ride down upon the cam surfaces 10 of said blocks and as they attain the positions shown by dotted lines, Fig. 4, the rearward movement of the table top is arrested by the abutment of the blocks 32 against 120 blocks 8, as hereinbefore explained. This sharp and final downward movement of the 125 table top to a horizontal position is permitted because the front portion of its beading 130 registers with and enters the recesses 16

and 17 hereinbefore described, and as it is forced down, the terminals 39 of the latches ride down and are repressed by the beveled catches 45 secured rigidly to the cross-bars

5 3. As the top attains a horizontal position in its rearward limit of adjustment, the terminals of said latches clear said catches and the springs 42 react and cause the terminals 39 to engage under the catches and thereby 10 prevent raising movement of the top until the latches are unfastened by applying pressure by hand on the handles 41.

At this time the front portion of the beading 30, not only enters the recesses 16 and 17 15 as explained, to permit the top to rest flatly upon the framework in dining table position, but also with the laterally-projecting portions of blocks 33, enters the recesses 27 in the upper edges of the leg-connecting 20 bars 26.

Near the front wall of the framework, catches 46, similar to the catches 45, project from the bars 3, and are adapted to be likewise automatically engaged by the latches 25 when the table top is drawn forward and then tilted down to normal or library table position, as shown by full lines in Fig. 4, and preliminary to the rearward adjustment of the said top, the handles of the latches must 30 be manipulated as explained, to disengage the latches from the catches 46. The engagement of the said latches with the catches 45 or 46, locks the top rigidly upon the framework, as will be readily understood.

35 35. To retain the top in position, and constitute a pivotal support and guide for the same in its pivotal and sliding movements, the top is provided in its underside with a pair of channels 47, extending from its rear 40 margin about halfway to its front margin, and said channels are partly underlapped from one side by strips 48, secured to the top and engaged by retainers. The retainers consist of rods 49, fastened to the backwall 45 of the framework and provided with inwardly-projecting ends or tongues 50, fitting over the said strips and within the said channels to hold the top upon the framework without interfering with the sliding 50 and pivotal action of the top.

To abut against bar 4 of the framework and thus guard against the drawer being completely withdrawn from the table, a pair of stop-blocks 51, are secured to the drawer 55 at its underside, and fitting upon the central guide-bar 23 to slide thereon, is a channeled slide 52 rigidly secured to and depending slightly from a slidable cross-bar 53 extending transversely of and within the drawer, 60 the channeled slide 52 serving to hold the cross-bar 53 slightly above the bottom of the drawer to avoid friction between said parts, and also guarding against twisting and binding movements of said cross-bar, 65 and said parts are prevented from moving

upward within the drawer by longitudinal retaining cleats 54, overlying the ends of the cross-bar and secured to and within the drawer.

Near the ends of the cross-bar 53 are secured a pair of bearing lugs 55, provided with vertical rearwardly-facing shoulders 56, and between said lugs is a top-extension 57, provided with a pair of wings, herein-after identified. Near its rear end the extension 57 is pivotally mounted on the central or body-portion of a U-shaped shaft 58, the arms or cranks 59 of said shaft, terminating in alined ends journaled in the said bearing lugs, the arrangement being such 80 that the extension of the top can be grasped and swung forwardly with the ends of said shaft 58 as the axis of such movement. The said shaft is of such proportion it will raise the rear end of the extension to the plane 85 of the top when the latter, after being adjusted rearwardly, is swung downward and secured in the position shown by Fig. 3. It will be noted by reference to the last-named figure, that the crank-arms of said shaft are 90 limited in their forward swinging movement by the rearwardly-facing shoulders 56, and that at such time the extension 57 is resting on the front wall of the drawer so that the closing movement of the latter re- 95 sults in the abutment of the inner edge of the extension against the front edge of the top, as shown by Fig. 1. It will be understood of course, that before the extension is withdrawn from the drawer to its elevated 100 position, the drawer must be fully opened, as indicated by Fig. 2, and that when the extension is grasped and raised until its front edge clears the front wall of the drawer, it can be pulled out until it attains the position shown most clearly in Fig. 3, the cam lugs 60 at the underside of the extension, 105 acting as levers to exert a lifting force on the rear end of the extension to facilitate the forward rocking action of the crank shaft, 110 and when the extension is released the square or abrupt ends of said lugs fit against the front side of the drawer to impart closing movement thereto when a backward push is applied on the extension. The ex- 115 tension is provided at its front edge with a depending bead 61, to conform to the bead of the top, and to lift said bead over the front wall of the drawer in returning the extension to position within the drawer, 120 cam lugs 62, are secured to the underside of the extension.

A pair of side wings 63, are hinged at 64, to the extension so as to be capable of lying inverted or folded upon it or of lying in 125 the same plane as and at opposite sides of the extension, and said wings are provided with beads 65, at their outer ends and sides, conforming to the beads of the top and the said extension thereof.

- When the parts have been disposed as shown by Figs. 2 and 3, the drawer is closed until arrested by the impingement of the rear end of the extension upon the front edge of the top. The wings are then unfolded until they rest upon the adjacent corners of the framework 1, as shown by the left-hand wing in Fig. 1, and fit squarely against the front edge of the top. To secure the wings in this position so that in conjunction with the interposed extension and the top, a dining table is provided which is strong and rigid, it is necessary to establish an interlocking relation between said wings and the framework. To accomplish this object in a simple and efficient manner the following construction is provided: A block 66, is secured to the underside of each wing to form a mount for a rock-shaft 67, provided with a handle 68, for operation in a recess 69, in the block. The rock-shaft also has a latch end 70, for operation in a recess 71, in the opposite side of the block from recess 69, and under a keeper 72, bridging said recess 71, and said shaft is held with its latch end advanced by a spring 73 secured in recess 69 and bearing against the handle of the said shaft. The framework 1, near each corner, is provided with a recess 74, to receive one of the latch ends when the respective wing is pressed down upon the framework, and adjacent each recess 74 is a beveled catch 75, to repress the latch end as the same passes down into the recess, the said latch end as it clears the lower edge of the said catch, snapping under the latter and thus locking the wing to the framework. The table is then ready for use as a dining table.
- 40 To reconvert the table into a library table, the operator reaches under the wings and applies pressure on the handles of the latches thereof to disengage the latches from the said catches, and at the same time applies upward pressure on the wings to swing the same to folded position upon the extension. The latches for the top are then tripped from engagement with the catches 45, to permit the table top to be tilted up at its front edge. The drawer is then pulled open to permit the extension and superimposed wings to be stored in an obvious manner within it, and is then reclosed, and as this is accomplished, the top is pulled forward until arrested by the blocks 32 striking the front wall of the framework and is then pressed down until the top-controlling latches pass and snap under the catches 46 and thus lock the top rigidly in place.
- 50 60 From the above description it will be apparent that I have produced a convertible table possessing the features of advantage enumerated as desirable in the statement of the object of the invention, and while I have illustrated and described the preferred em-

bodiment of the invention, it will be understood that it is susceptible of changes in form, proportion, detail construction and organization without departing from the spirit and scope of the appended claims.

70

I claim:

1. A table comprising a rectangular framework provided with recesses in the upper edges of its endbars, a single-piece top adjustable to completely or partly cover said framework and provided with a depending bead at its front edge to occupy a position forward of the framework or depend within said recesses; said top occupying the same horizontal plane in both positions of adjustment, and means for securing the top rigidly in either of said positions.

75

2. A table comprising a rectangular framework, a top normally covering the entire framework and adjustable rearwardly to uncover a substantial portion of the front part of the framework and overhang the latter at the rear thereof, means for preventing back and forth slidable movement of said top when in a horizontal position, and means for clamping the top flatly down upon the framework in a horizontal position when in its normal position or at the rearmost limit of its adjustment.

80

3. A table comprising a rectangular framework, a top normally covering the framework and adjustable rearwardly to uncover a substantial portion of the framework and overhang at the rear side of the latter, a latch mechanism and a pair of catches for respective engagement with the latch mechanism when the top is in its normal position or in its rearward position of adjustment, to clamp the top in horizontal position upon the said framework, and means for preventing forward or rearward movement of the top when the table top is in a horizontal position.

95

4. A table comprising a framework, a top upon said framework and susceptible of back and forth movement thereon, a pair of bars rigid with the framework and below the top, front and rear catches adjacent the ends of said bars, blocks depending from the top within said framework and engaging said bars at sides thereof, pins projecting from said blocks and adapted to stand at the front or rear ends of the latter or to pass along the upper edge thereof, and spring-actuated latch mechanisms carried by said blocks and adapted for automatically engaging the front set of catches when the top is in normal position and the rear set of catches when the top is at its rearmost limit of adjustment.

100

5. In a table, a rectangular framework provided with pockets and guide channels extending rearwardly from said pockets, a top slidingly and pivotally secured to said framework for back and forth and tilting movements and adapted to rest flatly and

105

110

115

120

125

130

horizontally on the framework at each end of its back and forth movement, front and rear catches secured to the framework, latches carried by the top and adapted to engage the front or rear catches when the top is flatly engaging the framework at one end or the other of its sliding adjustment, and means movable with the top for travel through said channels when the top is in tilted position and slidably moved, and for occupying said pockets when the top is at the forward limit of its adjustment; the front edge of said top when at the rear end of its movement, being rearward of the vertical plane of the front edge of the framework.

6. A table provided with a rectangular framework having ribs connecting its front and rear walls, corner legs secured to the framework, bars connecting the legs at corresponding ends of the framework and extending parallel with the end bars of the framework and said ribs, a top slidably and pivotally mounted on the framework for back and forth movement, said top being adapted to rest flatly and horizontally on the framework, at each end of its back and forth movement, and being provided with a pair of blocks between each rib and adjacent leg-connecting bar to guide the top in its sliding movement and to limit such movement by abutment against fixed parts of the framework, and means for rigidly securing the top in either of its adjusted positions to said framework; the front edge of said top when at the rear end of its movement, being rearward of the vertical plane of the front edge of the framework.

7. A table comprising a rectangular framework provided with recesses in the upper edges of its end bars and a recess in its front wall, a top adjustable to completely or partly cover the framework and provided with a depending bead at its front edge to occupy a position forward of the framework or depend within said recesses of the end bars, means for securing the top rigidly in either of said positions, a drawer slidable through and when closed filling the said recess in the front wall of the framework, a slide within said drawer, a rock-shaft having crank arms bearing a journaled relation to said slide, a top extension pivoted on the rock-shaft and adapted to lie within said drawer or to be supported in the plane of the top when the latter rests on the framework in its rearmost position, by said shaft and the front wall of the drawer and to abut at its rear edge the front edge of the top when the drawer is closed, a pair of wings hinged to the side edges of the extension to lie upon or to flank and lie in the same horizontal plane as said extension, and when in the last-named position abut the front edge of the top and lie upon said framework, and

means for rigidly securing said wings to the framework.

8. A table comprising a framework, a sliding drawer carried thereby, a top adapted to partly cover the framework, a slide within the drawer, provided with lugs near each side thereof, the lugs having rearwardly-facing shoulders, an extension for the top, a crank shaft forming a pivot for said extension and journaled at its ends in said lugs and adapted to swing forward until its crank arms abut said shoulders, to raise the rear end of said extension and permit its front portion to be deposited upon the front wall of said drawer in the horizontal plane of said top so that the rear end of the extension, when the drawer is closed shall abut the front edge of the top, wings hinged to opposite side edges of the extension to lie inverted upon the same when wholly within the drawer or to unfold and lie upon the corners of said framework and against the front edge of the top, and means to secure the wings firmly in the last-named position.

9. A table comprising a framework having a recess in its front wall and a top, a drawer slidable in the framework and when closed filling said recess, and provided with a central guide, a slide engaging said guide for back and forth movement in the drawer, a transverse bar carried by the guide, cleats secured to the drawer and overlapping the ends of said bar as a guide therefor, lugs secured to the said bar near its ends, a transversely extending rock-shaft within the drawer and journaled at its ends in said lugs, a table top extension pivoted to the rock-shaft between said lugs and adapted when pulled forward to cause the said shaft to rock and lift the rear end of the extension to the plane of the said top and to move the said slide and transverse bar forward, and lugs secured to the extension for engagement with the front side of the drawer to close the latter when pressure is applied on the said extension in a rearwardly direction.

10. A table, a rectangular framework provided with recesses in the upper edges of its end walls, guide bars parallel to and spaced inwardly from the end walls of the framework and forming pockets in conjunction with the front wall of the framework, a top for the table and normally covering the entire framework and provided at its front margin with a depending bead adapted to stand forward of the front wall of the framework or to depend into the recesses in the upper edges of the end walls, blocks depending from the said top adjacent said guide bars, and laterally projecting pins projecting from said blocks and adapted when the table top is in normal or forward position to stand in said pockets and when adjusted rearwardly with its said bead en-

gaging said recesses, to stand at the rear ends of said guide bars, catches adjacent the ends of said guide bars, and latch mechanisms carried by said blocks for engagement with said catches respectively when the table top occupies its forward or rearward position.

11. A combined library and dining table, comprising a framework, a top rearwardly adjustable on and adapted when adjusted to uncover the front part of said framework, a forwardly movable drawer in the framework, a three-part extension for the top abutting at its rear edge against the front edge of the top, two of said extension parts resting upon the uncovered corners of the framework, and the third extension part resting upon the front wall of the drawer and all of said parts lying in the same horizontal plane, and means for automatically locking the said extension parts resting upon the front corners of the framework, to the latter and for manual operation to effect unlocking of said parts.

12. A combined library and dining table,

comprising a framework, a top rearwardly adjustable on and adapted when adjusted to uncover the front part of said framework, a forwardly movable drawer in the framework, and a three-part extension for the top abutting at its rear edge against the front edge of the top, two of said extension parts resting upon the uncovered corners of the framework, and the third extension part resting upon the front wall of the drawer and all of said parts lying in the same horizontal plane; the extension parts resting on the corners of the framework being foldably connected to and adapted to rest upon the remaining extension part, and the latter having a movable connection with the drawer for adjustment with the companion extension parts wholly within the drawer or to a position partly supported upon and projecting forwardly beyond the front wall of the drawer.

In testimony whereof, I hereunto affix my signature.

ANDREW H. STONE.
